UNITED STATES PATENT OFFICE.

EDWIN R. GILL, OF NEW YORK, N. Y., ASSIGNOR TO ELECTRIC CONTRACT COMPANY, A CORPORATION OF NEW JERSEY.

PORTABLE ELECTRIC GAS-LIGHTER.

SPECIFICATION forming part of Letters Patent No. 761,372, dated May 31, 1904.

Application filed January 4, 1902. Serial No. 88,409. (No model.)

To all whom it may concern:

Be it known that I, EDWIN R. GILL, a citizen of the United States, residing in the city, county, and State of New York, have invented 5 a certain new and useful Improvement in Portable Electric Gas-Lighters, of which the following is a specification.

My present invention has relation to an improved form of gas-lighting device of that 10 type wherein a small conductor is made incandescent by closing circuit through it and a battery in the handle of the device.

My device consists of a neck carrying proper circuit-closers and the glowing conductor, the 15 whole being capable of attachment to a proper current-generating means in various ways, one of which is covered in the accompanying claims. It is important in devices of this character that when the battery gives out it 20 can be quickly, easily, and certainly replaced by any one, however unskilled in the electric arts. My invention provides means for attaining this end.

My device also provides means whereby 25 the glowing conductor can be easily replaced when destroyed, thus greatly prolonging the life and usefulness of the entire device. Where quantity current of low potential is used, as is necessary for this type of device, it is very 30 important that all oxidation at contact-surfaces be strictly avoided. For this purpose the circuit-maker for operating the lighter should be arranged to cause a rubbing contact where circuit is made and broken, thus keeping 35 the conducting-points bright. This is accomplished by cheap, simple, and reliable means in my device.

My invention also covers certain details of construction whereby the lighter can be conveniently constructed and repaired, the same being more fully set forth hereinafter.

In the accompanying drawings, Figure 1 shows a central longitudinal section of a preferred form of my lighter, the battery-cell 45 being shown in elevation. Fig. 2 is a plan view of my circuit-closers looking into the lower end of the neck along its axis. Figs. 3 and 4 are similar but partial views exhibiting successive positions of the operating circuit-

closer, and Fig. 5 shows a modified means of attachment between the battery and the neck.

My preferred form of neck comprises a thin spun-metal shell 1, screw-threaded to receive the battery or battery-casing, which shell is prolonged in a tube 2 of such a length 55 as to conveniently reach a gas-burner. The upper half of this tubular extension is screw-threaded, as at 3, to receive the removable tip hereinafter described. Within the tube 2 and below the threads 3 is located a contact-button 4, supported by suitable insulation 5 and connected to a conductor 6, insulated from the metal of the neck. Within the shell 1 there is carried on the end of the tube 2 an insulating-block 7, out through which the conductor 6 is carried to a suitable terminal, as the screw 8. The wire 6 is made somewhat longer than is absolutely necessary to reach to the terminal 8, as shown in Fig. 2. This is for convenience in adjusting and connecting 70 all the parts in the shell 1 in the manner described below.

The screw 8 secures in place a bent spring 9, shaped substantially as shown in the drawings, which spring is constantly connected by 75 means of the conductor 6 with the contact-button 4. The spring 9 bends widely around the block 7 and normally presses outward upon a pin 10 or other offset carried by the insulating push-button 11. This pressure 80 keeps the button normally in the extreme outward position shown in Figs. 1 and 2. Just beyond the pin 10 the spring recurses sharply upon itself, as shown at 12, being so proportioned as to touch the contact-button 85 13 when pressed inward by the button 11 and offset 10. As clearly shown in Fig. 1, the piece 11 is bifurcated at 14, straddling the tube 2 and being thus confined and guided when moved in and out.

Inspection of Figs. 2, 3, and 4 successively will show the production of sliding contact between the spring 12 and button 13 when the former is pressed inward. Fig. 3 shows the contact in existence near the tip of the 95 spring when the button 11 is partly pressed in, while in Fig. 4 this contact is seen to occur farther back when button 11 is pressed

down altogether. Between these two positions the two terminals 12 13 rub one on the other, and their surfaces are thus kept bright, reducing ohmic resistance at that point. The 5 button 13 is in permanent connection with a contact-spring 15, extending under the block 7. These various parts are calculated for convenience in assembling and should be put together as follows: The shell 1 and tube 2 10 having been joined by any means or being made in one piece, if desired, the button 11, with the pin or other offset 10, is slipped into place, straddling the tube 2, as shown. At this time the extra length of the conductor 6 15 is hanging down, so that its extremity is outside of the shell 1. The bared end of this wire is then secured under the screw 8, together with the spring 9, and the block 7 is then placed upon the tube 2, as shown, fitting tightly and being held in place by friction or otherwise. The spring 15 at this time is merely screwed down at 13, but is not bent down into the position shown in Fig. 1 20 until after the block 7 is in place. A little 25 channel is preferably provided across the lower face of the block 7 to accommodate the conductor 6. This is shown in end view in Fig. 1 just above the spring 15.

The battery 16 presses with one pole against 30 the spring 15, as shown in Fig. 1, in connection with a well-known form of dry battery-cell. The other pole of the battery is in electric connection with the outer metal casing of the device, and this connection may be accomplished 35 in a variety of ways. In Fig. 1 is shown a simple construction having this end in view. Here a battery-casing 17 of thin metal carries a bottom spring 18 for supporting the cell within the casing or, if desired, this spring may 40 be dispensed with. The top of the casing 17 is preferably threaded to screw into or upon the neck - shell 1. (See Fig. 1.) The parts are so proportioned that when the casing is 45 screwed home the battery 16 is pressed against the spring-terminal 15. This brings the outer metal shell of the combined casing and neck into continued electrical connection with the outer pole of the battery 16, while the other pole of the battery is in electrical connection 50 with the spring 15 and button 13. The conductor 19 in the removable tip 20 may be of platinum or other suitable material and of such dimensions as to be rendered suitably incandescent by the particular battery 16 used. The 55 lower end of the tip 20 screws into the tube at 3 and contains a suitable insulating-block 21. This block carries a lower terminal or conducting button 22, which comes in contact with 4 when the tip 20 is screwed home. The button 22 60 is electrically connected through wire 23 with one end of the glow-conductor 19, the other

end of which is connected through wire 24 to the outer metal shell or casing of the device.

To light a gas-jet, it is only necessary to press the button 11 and hold the filament 19 65 near the gas. The circuit passes from one pole of the battery 16 through spring 15, terminals 13 and 12, by wire 6 and buttons 4 and 22 to the conductor 19, returning through the outer shell of the neck and battery-casing 70 to the spring 18 and the exterior pole of the battery. Here the battery 16 is simply provided with a thread 25, which is adapted to coöperate with the thread on the shell 1 to hold the battery in place. In this form the 75 battery 16 will become the handle of the device.

It will be seen that in this device means are supplied for replacing the battery or the 80 glowing filament when either is worn out.

I am not to be understood as confining myself to the precise details of structure herein shown and described, as many of these may be modified without departing from the principle of my invention.

What I claim is—

1. In an electric gas-lighter, a battery, a casing therefor, an insulating-base within said casing, a fixed terminal on said base, a spring-terminal also fixed to said base at one end of 90 its ends and curved partly around said base so as to bring its free end near said fixed terminal, and a push-button projecting through said casing and against said spring-terminal so as to bend it in a slanting direction against 95 the fixed terminal causing frictional contact, substantially as described.

2. In an electric gas-lighter having an extended neck, an insulating-block supported by one end of said neck, circuit-closers carried thereby and an insulating push-button straddling said neck for operating said circuit-closers.

3. In an electric gas-lighter, a chamber for the necessary contact-making devices, an extension outside of the chamber and projecting partly into it, a filament on said extension, a conductor passing from said filament down said extension and into said chamber, a removable push-button straddling said extension within said chamber an insulating-block carried by said extension under said push-button, a fixed terminal on said block for said conductor, a spring connected to said terminal and bearing on said push-button to push it outward and a second fixed terminal on said block opposite the end of said spring.

EDWIN R. GILL.
